UNITED STATES PATENT OFFICE

2,491,552

ELECTRIC TROUBLE LIGHT

Carl Tom De Grace, Redondo Beach, Calif.

Application July 26, 1946, Serial No. 686,487

1 Claim. (Cl. 173—328)

1

My invention relates to tools and more particularly to an electric tool holder having means for interchangeably mounting different types of implements.

One object of the invention is to provide a novel tool adapted to be quickly connected to a battery such as may be used in an automobile or shop for various purposes.

Another object is to provide a novel holder for different interchangeable implements, such as light bulbs and soldering electrodes or the like.

And a further object is to provide in a tool, a novel clip arrangement adapted to serve as an electrical socket or holder for different electrically operated implements.

Other objects and many particular advantages of this invention will appear from the following detailed description, when considered in conjunction with the accompanying drawing, wherein like reference character in the description refer to like reference characters for the several parts of the invention illustrated in the drawing.

Figure 1 is a side longitudinal cross section of the novel tool showing an electric bulb mounted in the adjustable socket or clip portion thereof.

Figure 2 is a side view of the socket clip.

Figure 3 is a view of a carbon electrode, such as may be mounted in the socket in place of the electric bulb.

Figure 4 shows a ground connection for use with the electrode.

Referring to the drawing in detail, the device comprises a handle 10 formed of insulation, such as hard rubber, synthetic resin, such as phenol-formaldehyde condensation product generally known as "Bakelite" or other suitable material. The handle contains a central longitudinal bore 11 through which extends a wire or cable 12 for connection to a source of electric current such as may be supplied by a storage battery for example. The cable 12 extends from the rear of the handle 10 for several feet and is bent around a screw 14 on the end of a metal clip 15. The other end of the cable 12 is similarly secured to a second similar metal clip 16 which is mounted by a screw 17 in the front end of the handle 10 in a socket connected with the bore 11.

The clips 15 and 16 may be of any suitable type, such as the well-known "alligator" type, see Fig. 2, comprising a pair of gripping jaws 18 and 19 pivoted together, with a handle extension 20 carried by jaw 19 and a spring 21 adapted to normally bias or urge jaws together.

Mounted in the side of the handle near the front end thereof in a socket 22 is a combined

2

hanger for the tool and ground connection for the tool when operating a lamp. This hanger comprises a flat rod 23 with a hooked end 24, from which a wire 25 may be connected to ground the socket connection, while the other end has a projection 26 extending at right angles to the axis of the rod 23 seated in the socket 22. Threadedly mounted in the rod 23 is a threaded bolt 27 adapted to thread into the body of the handle 10 intermediate the socket 22 and this front tip end of the handle 10. This bolt 27 when threaded into the handle at this point serves to secure the rod 23 to the handle 10.

The flat rod 23 is resilient and when the flat side thereof near its free hooked end 24 engages with the base of an electric light bulb or lamp 28, it is yieldable in cooperation with the jaws of the holder clip 16.

Thus a firm electrical socket connection is made by the jaws 17 and 18 and the rod 23.

To use the tool as a trouble light the clip 15 is connected to the positive battery terminal of an automobile and the hook 24 may be hung over any suitable part of the automobile in proximity of the parts to be worked on with the lamp 28 in the jaws 18 and 19 of clip 16.

Other implements may be clamped between the jaws, such as the carbon electrode 30 shown in the drawing. This electrode 30 fits between the jaws with its base 31 on the flat rod 23 in a similar manner to the lamp 28.

For use as a soldering tool an additional wire connector, see Fig. 4, is provided with terminal clips on each end to connect from the hook 24, so as to ground the socket connection through the automobile frame or direct to the battery.

When a circuit is completed by the clip 16, and the connecting wire 12 in the handle bore 11 current flows to the electrode 30, and it becomes heated for use as soldering tool, or the like.

Thus I have provided a very simple tool, economical to manufacture and of but few parts of rugged and durable character, which can be used by simply clipping the same into an electrical circuit of an automobile, for example, or to the terminal posts of a storage battery in the work shop.

While I have illustrated and described my invention in detail for only one embodiment thereof, it is to be understood that changes which may occur to others skilled in the art are also to be considered as part of my invention.

What I claim is:

A holder for an electrically operated unit such as an incandescent lamp having a metal base

terminal and a central base contact, comprising a relatively long handle body of insulation material having a socket in one end, a relatively long spring clip having two coacting jaws at one end and having its other end secured in said socket whereby the clip extends longitudinally from the end of the handle, the jaws being adapted to receive and grip the metal base of said unit, an electric current conductor electrically connected at one end with the said other end of the clip, a relatively long flat resilient current conducting strip positioned at one end against the side of the handle at the said socketed end of the handle and extending longitudinally of the handle in spaced relation with a side of the clip, the other and free end of said strip terminating in a position relative to said jaws to be electrically contacted with the center base terminal of the unit secured between the jaws, a hook member of electric conducting material carried by the said other end 20 of said strip upon the side thereof opposite from

said clip jaws, said hook member serving the double function of a suspension means for the holder and a means for connecting an electric current conductor with the strip.
